UNITED STATES PATENT OFFICE.

EMIL H. JOURDAN AND WILLIAM M. YOUNG, OF NEWARK, NEW JERSEY.

WINDOW-SCREEN SUPPORTER.

1,263,066.

Specification of Letters Patent. Patented Apr. 16, 1918.

Application filed July 5, 1917. Serial No. 178,803.

To all whom it may concern:

Be it known that we, EMIL H. JOURDAN and WILLIAM M. YOUNG, citizens of the United States, residing at Newark, in the county of Essex, State of New Jersey, have invented certain new and useful Improvements in Window-Screen Supporters; and we do hereby declare the following to be a full, clear, and exact description of the invention, such as will enable others skilled in the art to which it appertains to make and use the same.

This invention relates to new and useful improvements in windows, and has for its primary object to provide means for securing a window screen in the window opening.

A further object of the invention is to provide a plurality of window screens by means of which the screen is positively held against displacement from the window opening when the holder is in one position.

A further object of the invention is to provide a screen holding device by means of which the screen is readily removable from the window opening as desired.

Referring to the drawings,

Figure 1 is a view in elevation of a window opening showing the position of the parts when the screen is removed therefrom.

Fig. 2 is a vertical sectional view on the line 2—2 of Fig. 1 showing the screen removed,

Fig. 3 is a transverse sectional view on the line 3—3 of Fig. 1, and;

Fig. 4 is a detail view.

Referring more particularly to the drawings, the reference character 10 designates a window frame, and 11 designates the window screen.

Secured to the opposite sides of the window frame 10 there is a U-shaped metal guide 12 which is rigidly secured to the window frame by means of screws or the like 13, and both of said guides have their upper ends beveled as at 14 for a purpose to be hereinafter described. These guide members are of a length substantially equal to half of the window frame, and are rigidly secured therein. Mounted on the opposite sides of the upper portion of the window frame 10 there are two guides 15, these guides being pivotally secured intermediate of their ends as by the screws 16.

The lower end of each of these guides is beveled as at 17 to conform to the beveled end 14 of the guides 12. These guides 15 are of substantially the same shape as the guides 12, and are adapted to be a continuation thereof so that they will receive the screen frame in its vertical sliding movements. By reference to Fig. 4 it will be seen that one of the lower guide members 12 is provided with a slot 20 and mounted in said slot 20 there is a member 21 which projects into the guide member 12, and this member 21 is resiliently secured by means of a spring 22 which in turn is rigidly secured as at 23. By this arrangement it will be seen that the screen may be held in adjusted position throughout the length of the window opening, and that if said screen frame engages both the guide members 12 and guide members 15, the guide members 15 will be prevented from moving about the pivotal points 16. It will be further noted that when the screen is positioned in the guide members 12 the same is securely retained within the window opening.

If, however, it is desired to remove the window screen, the screen is reciprocated vertically of the window opening until it is retained within the guide members 15. When this has been done, it will be seen that merely by grasping the bottom edge of the screen and pulling the same inwardly of the window frame, the guide members 15 will rock on their pivots 16 until their lower ends move out of alignment with the upper ends of the lower guide members 12 in which position the screen will be free to be removed from the window opening.

From the foregoing it will be seen that the present invention provides means for securing a window screen within a window opening, and at the same time means is provided by which the screen may be readily removed from the window opening when desired.

Having thus described the invention what is claimed is,

In combination with a window opening a plurality of oppositely disposed guide members mounted on the inner edges of the lower portion of the window opening and rigidly secured thereto, a plurality of oppo-

sitely disposed guide members pivotally carried by the opposite end of the window opening, a screen movable longitudinally of the rigid and the pivoted guide members, 5 and means carried by one of the rigid guide members and adapted for engagement with said screen to hold the screen in adjusted position relative to the window opening.

In testimony whereof we affix our signatures in the presence of two witnesses.

MR. EMIL H. JOURDAN.
WILLIAM M. YOUNG.
